(57) **CLAIM**

The ornamental design for a laser light, as shown and described.

DESCRIPTION

FIG. 1 is a rear view of the laser light showing the new design;

FIG. 2 is a front view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view of the front, bottom and right side thereof;

FIG. 8 is a perspective view of the front, left and top side thereof; and,

FIG. 9 is a perspective view of the rear, right and top side thereof.

The broken lines shown on the drawings depict portions of the laser light that form no part of the claimed design.
